(57) **CLAIM**

The ornamental design for a base member of a portable lift system, as shown and described.

DESCRIPTION

FIG. 1 is a perspective view of a base member of a portable lift system showing my new design;

FIG. 2 is a left elevational view thereof;

FIG. 3 is a right elevational view thereof;

FIG. 4 is a front elevational view thereof;

FIG. 5 is a back elevational view thereof; and,

FIG. 6 is a top plan view thereof.

The broken line showing in the figures is for the purpose of illustrating environment and forms no part of the claimed design.

1 Claim, 5 Drawing Sheets
